2 SHEETS—SHEET 2.

UNITED STATES PATENT OFFICE.

EDWARD F. ROBERTS, OF DETROIT, MICHIGAN, ASSIGNOR TO PACKARD MOTOR CAR COMPANY, OF DETROIT, MICHIGAN, A CORPORATION OF MICHIGAN.

GEAR-CUTTING MACHINE.

1,108,623.

Specification of Letters Patent. Patented Aug. 25, 1914.

Application filed October 15, 1912. Serial No. 725,954.

To all whom it may concern:

Be it known that I, EDWARD F. ROBERTS, a citizen of the United States, and resident of Detroit, Wayne county, State of Michigan, have invented certain new and useful improvements in Gear-Cutting Machines, of which the following is a specification.

This invention relates to gear cutting machines and particularly to improvements in 10 the type of machine described in Patents No. 294,844, dated March 11, 1884, and 665,054, dated January 1, 1901. Both of said patents relate to machines for cutting gears of the bevel type, on what is called in 15 the earlier of said patents the "principle of evolution". These patents, however, are limited to the theory of, and machines for, cutting true bevel gears as distinguished from skew bevels or gears having curved or 20 irregularly shaped teeth.

An object of the present invention is to render machines of this type capable of readily cutting skewed teeth in bevel gears, or curved or other teeth, which necessitates 25 the tool passing diagonally across the face of the gear blank during the cutting operation.

Other objects of the invention will appear 30 from the following description, taken in connection with the drawings which form a part of this specification, and in which,

Figure 1 is a side elevation and part section of a machine embodying the invention; Fig. 2 is a plan view of the same; and Fig. 35 3 is an enlarged vertical sectional view of the head portion of the ram and the parts mounted thereon.

Gear cutting machines of the type described in said patents usually comprise a 40 frame or base portion with blank holding and operating mechanism mounted at one end of the frame and tool holding and operating mechanism mounted at the other end of the frame. These two mechanisms are so 45 associated and timed in their operation that the blank is properly held in position for the tool to work upon it, the tool is lifted on its return stroke, during which period the blank is properly spaced from one tooth to another to allow the tool to operate upon the teeth consecutively, and the blank holding means is bodily rolled upon its former-cone for the purpose of generating the curved face of the tooth. In the present invention 55 it is intended that the blank holding and op-

erating mechanism and the tool holding and operating mechanism shall be so arranged that one may be adjusted to an angular position relative to the other. As an illustration of one way to accomplish this purpose, I have shown in the drawings the tool holding and operating mechanism as mounted upon a support which is adapted to oscillate about a vertical pivot arranged adjacent the geometric center of the machine. 60 This form of the machine will now be described.

The frame or bed of the machine is indicated at 20, and at the left hand end shown in the figures is mounted means for supporting and operating the gear blank. This supporting means consists principally of a plate 21 mounted upon a flat upper surface 22 of the frame, and having a series of circular grooves 23 in which fit the corresponding circular flanges 24 of a securing plate 25, which is fastened to the frame by the screws 26. The circumference of the plate 21 is formed with gear teeth 27, with which meshes a worm 28 driven by a shaft 29, 70 whereby the plate 21 is rotated or oscillated about a vertical axis which passes through the apex of the former-cone, hereinafter described.

The plate 21 carries two uprights 30 between which is adjustably held a block or bearing 31, as by bolts 32. Thus this bearing is adjustable about the apex of the former-cone for operation upon different sized gears or blanks. The blank 33 is 75 removably clamped to the arbor 34 which operates in the bearing 31, and upon the upper end of the arbor is rotatably mounted the housing 35 of the spacing head, the lower part of this housing comprising the former-cone 36, which is a production of the pitch cone of the blank 33. By means of two steel bands 37, each of which has one end attached to the cone 36 and the other to the body of the machine in such a way 80 that one band prevents the sliding of the cone in one direction and the other in the other direction, the said cone being so held that when the grooved plate 21 is oscillated, the cone will assume a motion as of a cone 85 rolling on a plane without slip. If the housing 35, of which the said cone is a part, were coupled to the blank arbor 34, this rolling motion would be transmitted to the blank 33, thereby imparting to the latter that mo- 90

110

tion which is necessary to cause the tool to generate the proper tooth contour. As a matter of fact, however, the housing 35 is only intermittently coupled to the arbor 34—namely, during the forward stroke of the tool. During the return stroke of the tool, the blank arbor is rotated in relation to the housing 35 through the distance, preferably, of one tooth of the blank 33. This 10 intermittent rotation is accomplished by a well known mechanism, such as that illustrated in said Patent No. 665,054, and need not be described in detail here. Also the shaft 29 is operated through gears 83 and 81, 15 universal joints 79, telescoping shaft 80, gears 77 and 76 from spindle 67, hereinafter described.

Upon the right hand end of the frame 20, as shown in Fig. 1 of the drawings, the 20 mechanism for operating the cutting tool is mounted. The base or support 62 of this mechanism is shown as resting on the frame in a circular groove or runway 63, and may thus be moved about the axis of a pin 64, 25 which is adjacent the lower end of the blank arbor 34, and which forms a connection between the support 62 and the frame 20. The support may be secured in its adjusted position by means of a set screw 65, and in Fig. 30 1 it is shown for convenience of illustration as secured in its central position, while in Fig. 2 the support is adjusted to a diagonal position for cutting skewed teeth. Upon the support 62 is a bearing 66 for the arbor or spindle 67 above referred to, which arbor carries a driving pulley 68 having an adjustable crank 69 thereon. By means of a connecting rod 70 this crank is connected with a ram 71, having a tool operating head 72 at its forward end. For operating the spacing mechanism at the left hand end of the machine, the driving pulley 68 carries a gear wheel 73 which engages with a pinion 74 mounted in an arm 75 extending from the bearing 66. This pinion 74 is coupled to a flexible shaft 40, which extends to the spacing mechanism referred to.

It will of course be understood that the 50 ram 71 slides longitudinally in suitable ways in the support 62. The tool operating head 72 is formed with a horizontal dovetail groove 84, and a tool support 85 has a dovetail 86 fitting said groove, whereby the tool support may slide transversely of the longitudinal axis of the ram. An apron 87 is pivoted on the support 85 by a pin 88, and a tool holder 89 is adjustably secured to the front face of the apron. The securing means for the tool holder comprises a block 90 sliding in a groove in the apron, and a pair of clamping plates 91 and 92 between which the tool holder 89 is held by bolts 93 and 94. In the forwardly projecting arm 95 of the tool holder 89 is secured a tool or cutter 96, which is adapted to traverse the

face of the gear blank 33 and cut the spaces between the teeth in the well known manner. For the purpose of cutting curved teeth or teeth of irregular shape, the tool support 85 may be connected with means for 70 sliding it transversely of the longitudinal axis of the ram 71 simultaneously with the reciprocation of said ram. As shown in the drawings, this means consists of an arm 97 secured to the tool support 85, as shown in 75 Figs. 1 and 2, and having a pin or roller 98 adapted to operate in a cam slot 99 in a cam plate 100, which is secured preferably to the support 62 or other part of the machine frame. The cam slot 99 may be of any desired shape, but for the purpose of cutting curved teeth said slot is in the form of an arc, as shown particularly in Fig. 2.

From the above description, it will be seen that as the ram 71 reciprocates through the medium of the connecting rod 70 and crank 69, the head 72 is carried with it, and the tool support 85 in moving forwardly is guided by the cam slot 99, and caused to slide transversely in the head 72 simultaneously with its forward movement. On the return stroke of the ram, the tool support 85 is of course caused to reverse its sliding movement in the head 72, and the parts are returned to initial position. This combined forward and transverse movement of the tool support 85, by reason of the curved cam slot 99, causes the tool 96 to move back and forth across the face of the gear blank in a curved path, which is substantially 100 parallel to a plane tangent to the pitch cone, thus cutting a curved space between the teeth, instead of a straight one as it would do without the cam mechanism. It will be observed that the support 62 is movable 105 parallel to the aforesaid tangent plane and the adjustment of this support varies the amount of angularity or skewing of the teeth, as above described.

It is desirable to raise the tool during its 110 return stroke so that the blank may be rotated for a cut on the next tooth, and for this purpose the apron 87 is provided with an offset arm 103, on the end of which is mounted a long roller 104. An arm 105 extending 115 from the support 62 has a lever 106 pivoted at 107, and said lever is provided with a roller 108, which operates in an irregular cam slot 109 in the face of the pulley 68, so that the forward end of the lever 106 120 depresses the arm 103 as it contacts with the roller 104. The roller is made sufficiently long to be operated upon by the lever 106 at any time during the transverse reciprocation of the tool support 85. By the 125 action of this lever 106, the tool is alternately raised and lowered, the cam slot 109 being so timed that the tool will be raised during the return stroke and will be in its normal cutting position during its forward 130

stroke. The tool and apron are shown in cutting position in Fig. 1, and in raised position as they would appear on the return stroke in Fig. 3.

5 In a pair of bevel gears the teeth of one gear are of course curved in the opposite direction to the teeth of the other. Therefore it is desirable to make the cam plate 100 reversible so that a single cam may be 10 used for cutting bevel gears of a pair. In preparing the machine for the reverse cut, besides reversing the cam, the support 62 is oscillated about the pin 64 to the opposite position at the other side of the geometric 15 center X of the machine.

It is believed that the operation of the machine will be clearly understood from the above description, taken in connection with the two patents above referred to.

20 It will be understood that the invention is not limited to the specific form of the machine shown herein, but is capable of modification in various ways without departing from the scope of the claims.

25 Having thus described my invention, what I claim and desire to secure by Letters Patent, is:

1. In a gear cutting machine, the combination with the bed thereof and former-cone, of a support adjustably mounted on 30 said bed and arranged to be bodily moved about an axis perpendicular to the plane upon which the former-cone rolls, blank holding and operating mechanism including 35 said former-cone and the surface upon which it rolls, and tool holding and operating mechanism, one of said mechanisms being mounted on said adjustable support and the other said mechanism being mounted on 40 said bed.

2. In a gear cutting machine, the combination with the bed thereof, and means for holding the blank, of a support for the tool operating mechanism adjustably mounted 45 on said bed, and arranged to be bodily moved about a vertical axis adjacent the blank, a tool operating head mounted on said support to reciprocate substantially in a plane across the face of the blank, a tool 50 support mounted to slide in the head, means for reciprocating the head, and means for simultaneously sliding the tool support.

3. In a gear cutting machine, the combi-

nation with the bed thereof, and means mounted on said bed for holding the blank, 55 of tool holding and operating mechanism mounted on the bed, and means permitting adjustment of the tool holding mechanism, relative to the blank holding mechanism, parallel to a plane which is tangent to the 60 surface of the blank, said tool operating mechanism comprising means for operating the tool in a curved path across the face of the blank.

4. In a gear cutting machine, the combination with the bed, and blank holding and operating mechanism mounted thereon, of a tool supporting head mounted for reciprocation on said bed, means for operating said head, means permitting adjustment of the 65 part of said bed supporting the head relative to the blank holding mechanism, and means for causing a relative movement between the blank and the tool in a horizontal plane but transversely to the reciprocating 70 movement of the head and simultaneously 75 with the latter movement.

5. In a machine for cutting bevel gears, in combination, the bed or frame, means mounted on the bed for holding and feeding 80 the blank, a tool holding and operating mechanism including means for moving the tool in a curved path across the face of the blank and substantially parallel to a plane tangent to the conical pitch surface of the 85 blank, and a movable support for said mechanism, on said bed, permitting the mechanism to be adjusted parallel to said tangent plane.

6. In a gear cutting machine, in combination, means for holding and feeding the gear blank, a tool holding and operating mechanism comprising means for moving the tool in a curved path across the face of the blank and substantially parallel to a 95 plane tangent to the conical pitch surface of the blank, and means permitting the adjustment of said tool holding mechanism relative to said blank holding means substantially parallel to said tangent plane. 100

In testimony whereof I affix my signature in presence of two witnesses.
